(57) **CLAIM**

The ornamental design for a feminine exercise device, as shown and described.

DESCRIPTION

FIG. 1 is a front perspective view of the first embodiment of a feminine exercise device showing the new design on a reduced scale; the handle loop element shown in broken lines forms no part of the claimed invention;

FIG. 2 is a bottom perspective view thereof;

FIG. 3 is a front view thereof; the rear view being a mirror image thereof;

FIG. 4 is a top view thereof;

FIG. 5 is a bottom view thereof;

FIG. 6 is a left side elevational view thereof; the right side elevational view being a mirror image thereof;

FIG. 7 is a front perspective view of the second embodiment of a feminine exercise device showing the new design on a reduced scale; the handle loop element shown in broken lines forms no part of the claimed invention;

FIG. 8 is a bottom perspective view thereof;

FIG. 9 is a front view thereof; the rear view being a mirror image thereof;

FIG. 10 is a top view thereof;

FIG. 11 is a bottom view thereof; and,

FIG. 12 is a left side elevational view thereof; the right side elevational view being a mirror image thereof.
